UNITED STATES PATENT OFFICE.

JAMES HARRY KEIGHLY McCOLLUM, OF TORONTO, ONTARIO, CANADA.

AUTOMATIC TRAIN-STOP.

1,150,377.

Specification of Letters Patent. Patented Aug. 17, 1915.

Application filed May 3, 1909. Serial No. 493,670.

To all whom it may concern:

Be it known that I, JAMES HARRY KEIGHLY McCOLLUM, a subject of the King of Great Britain, and resident of the city of Toronto, county of York, Province of Ontario, in the Dominion of Canada, have invented certain new and useful Improvements in Automatic Train-Stops, of which the following is a specification.

10 The invention relates to improvements in automatic train-stops, as described in the following specification and illustrated in the accompanying drawings that form part of the same.

15 The invention consists essentially in the novel construction and arrangement of parts, whereby a stationary contact member ordinarily in the path of a contact member extending from the vehicle has the effect 20 of operating the arresting mechanism in said vehicle, and whereby electric means are adapted to render the stop mechanism inoperative under certain conditions.

The objects of the invention are, to devise 25 a train stop mechanism which may be controlled by present known signaling systems and which will automatically stop the train in the event of the failure of the engineer to observe a danger signal, or a failure in 30 any of the electrical connections.

In the drawings, Figure 1 is a diagrammatic view of my invention showing the electrical connections to a signal circuit and to the electrically operated mechanism on 35 the train. Fig. 2 is a cross sectional view showing the obstructing member and valve mechanism.

Like numerals of reference indicate corresponding parts in each figure.

40 Referring to the drawings, 1 is the stationary obstructing member in the form of an inverted T section formed with its upper edge arranged in two levels 2 and 3, the upper level 3 being connected to the lower level 2 by the sloping sections 4 and the extreme ends 5 being sloped downwardly from the said lower levels. The stationary member 1 is supported on suitable insulating

blocks adjacent to and parallel with the ordinary running rail 6 with its lower level 50 raised slightly above the level of the top of the rail 6.

7 is a guard supported on the posts 8 a short distance above the member 1 adapted to protect the said member 1 from accumulations of sleet.

9 is the electrical signal circuit leading from a block in the running rails in advance of the stationary member and having included therein the semaphore 10 and the electro-magnet 11.

12 is an independent electric circuit electrically connected at one end to the member 1 and at the other end to the running rails 6 and having interposed in the length there- 65 of an electric switch 13 operated by the electro-magnet 11.

The signal circuit herein shown is of the "normal power held clear" type and requires the electric current to be flowing 70 therethrough in order to hold the semaphore to indicate a "clear" track ahead. In the event of the circuit 9 being short circuited by a train or car, or in the event of the circuit being broken through any cause, the 75 holding power of the electro-magnet 11 will be impaired, and the switch 13 be allowed to swing open to break the circuit 12, and the signal 10 be moved by its internal mechanism to "Danger". 80

14 is a lever or shoe movably supported on the locomotive in such a manner that it may be raised or lowered and said lever is operatively connected to a suitable valve mechanism 15 adapted to open the train line 85 pipe 16 of the automatic air brakes, in the event of the said lever 14 coming in contact with the obstructing member 1. The lever and valve are suitably insulated from the locomotive. 90

17 is an electrically operated mechanism here shown in the form of an electro-magnet and solenoid adapted, upon being energized, to lift the lever 14 and valve 15 so that the said lever will clear the obstructing member 1 in the passage of the train, the valve 15 95

being connected to the train line pipe by a flexible connection 18.

The lever or shoe 14 is arranged so that in its lowermost position it just clears the lower levels of the obstructing member 1 and if retained in the lowermost position will be swung upwardly through the inclined or sloping portion of the member 1 to the upper member 3, the swinging thereof opening the valve 15 and allowing the escape of air from the train line and consequently actuating the brake mechanism and stopping the train.

19 is a hinged shoe fixedly supported from the locomotive and insulated therefrom and set on a slightly lower level than the shoe 14 so that it will engage and make contact with the obstructing member 1 on the extreme sloping ends 5, said shoe being so placed that it will engage the said member 1 before the shoe 14 reaches the sloping portion 4 of the obstructing member.

20 is a wire leading from the shoe 19 to the electrically operated mechanism 17 for raising the shoe 14, and 21 is a wire leading from said electrically operated mechanism and electrically connected to the frame of the locomotive.

22 is an electric circuit arranged in parallel electrical connection with the wire 20 and having a switch 23 therein arranged and an electric bell 24.

25 is an electro-magnet included in the circuit 20 and arranged to close the switch 23 on the flow of current through the wire 20 thus closing the parallel circuit through the bell 24.

In the operation of this device, the current, flowing through the signal circuit 9, energizes the electro-magnet 11 and attracting its armature, closes the switch 13, thus electrically connecting the member 1 with the rail 6. As the locomotive approaches the member 1 the shoe 19 comes in contact with the said member and through the frame and wires 20 and 21 closes the electric circuit 12. The current, flowing from the battery in said circuit through the mechanism 17, operates said mechanism to lift the shoe 14 clear of the obstructing member, consequently the train will pass the obstructing member. The current, flowing through the circuit 12, energizes the electro-magnet 25 and closes the switch 23 throwing the electric bell 24 into parallel electrical connection and giving a positive "proceed" signal to the engineer, the said bell being arranged in the cab of the locomotive. In the event of the short circuiting of the circuit 9 by another train being in the signal block in advance of the said train and cutting out the battery in the block, the cessation of flow of electric current causes

the semaphore 10 to indicate danger and as the electro-magnet 11 is then de-energized, 65 the switch 13 is opened, being spring or gravity operated to open from its closed position on the breaking of the signal circuit. In the event of a train approaching the stationary obstructing member 1 when a "danger" signal is displayed in the signal circuit, the circuit 12 is de-energized, therefore there will be no current to flow through the equipment on the locomotive and consequently the shoe 14 will remain in its lower- 70 most position, with the result that said shoe will engage the sloping portion 4 of the member 1 and be tilted to operate the valve 15; opening said valve and making an automatic application of the brakes on the 80 train. The upper length of the obstructing member may be made any desired length to hold this valve open or suitable mechanisms may be arranged to hold the valve open once it is operated, until the train is 85 brought to a stop.

The parts herein shown and described are merely diagrammatic in form and it must be understood that any suitable valve mechanism or electrically operated mechanism 90 may be used without departing from the spirit of the invention so long as the main feature is adhered to, that is to say, so long as the brake mechanism is operated by the contact of a movable member supported on 95 the locomotive with a stationary obstructing member arranged in its path, the former being operated to render the stop mechanism inoperative when normal conditions are to give the train a clear passage.

The preferable method of rendering temporarily inoperative the mechanism for actuating the arresting mechanism of the train has been described but the same object may be attained without departing from the 105 spirit of the invention, that is to say, it has been explained that the said mechanism is rendered inoperative by being lifted clear of the obstructing member but the contact arm or shoe may be fixed and the valve 110 mechanism rendered temporarily inoperative by the electrically operated mechanism.

What I claim as my invention is:—

1. In an automatic train stop, a brake 115 mechanism on the train, a member adapted to operate said mechanism and movably supported on and projecting from the train, a stationary obstructing member arranged in the path of said projecting member, electrically actuated means for moving said projecting member to clear said obstructing member, a shoe projecting from the train, a partial circuit connected with said shoe and with the running gear and including said 120 electrically actuated means, and a partial

- 5 circuit connected with the obstructing member and with the track rails adapted to co-operate with the first named partial circuit when said shoe engages the obstructing member.
- 10 2. In an automatic train stop, a vehicle, a contact member extending from said vehicle, an arresting mechanism on said vehicle controlled by the movement of said contact member, a stationary contact member arranged in the path of the aforesaid contact member, an electric signal circuit energized under normal clear trackway conditions, an open electric circuit controlled by said signal circuit and connected with said stationary contact, an electric contact engaging said stationary contact before said first named contact member engages said stationary contact, and an electric mechanism in the vehicle 15 connected with said electric contact and adapted in operation to withhold the actuating of the arresting mechanism during the energization of said signal circuit.
- 20 3. In an automatic train stop, a vehicle, a contact member movably supported on and extending from said vehicle, an arresting mechanism operatively connected with said contact member, a stationary contact member arranged in the path of the aforesaid contact member, a signal circuit and means operated from said signal circuit for moving said movable contact member to clear said stationary contact member.
- 25 4. In an automatic train stop, a vehicle, a contact member movably supported on said vehicle and extending therefrom, an arresting mechanism on the vehicle operated by said contact member, a stationary contact member arranged in the path of the aforesaid contact member, an open electric circuit connected to said stationary contact, an electric mechanism on the vehicle for moving said actuating means to clear the said obstructing member, and means contacting 30 said stationary contact member and closing the electric circuit through said electric moving means.
- 35 5. In an automatic train stop, the combination with the train line pipe of the arresting mechanism on a vehicle having an opening therefrom and a valve closing said opening, of means for opening said valve movably supported on the vehicle and projecting therefrom, a stationary contact member arranged in the path of said valve operating means, an open electric circuit connected with said stationary contact, electrically operated means for moving said valve operating means to clear said stationary contact member, and means for closing an electric circuit through said electrically operated means through contact with said stationary contact.
- 40 6. In an automatic train stop, the combination with the train line pipe of the arresting mechanism on a vehicle, of a shoe movably supported on the vehicle and projecting therefrom, a valve operatively connected with said shoe and moving therewith and adapted to open said train line pipe, a stationary contact member arranged in the path of said shoe, electrically operated means for moving said shoe and said valve so that said shoe will clear said stationary contact member, an open electric circuit connected with said stationary contact, and a shoe supported from the train and insulated therefrom and electrically connected to said electrically operated means and adapted to contact with said stationary contact member 45 and close the electric circuit through said electrically operated means.
7. In an automatic train stop, the combination with the train line pipe of the arresting mechanism on a vehicle, of a pivotal shoe movably supported on the vehicle and projecting therefrom, a valve operatively connected with said shoe and closing an opening from said train line pipe, a stationary contact member arranged adjacent to the running rails and having inclined surfaces, an open electric circuit connected to said stationary contact member and to the running rails, said circuit having a switch interposed therein, an electrically operated mechanism operatively connected to said shoe and valve and adapted to raise said shoe clear of said stationary contact member in the passage of the vehicle, a shoe supported on the vehicle and adapted to contact with said stationary contact member at a lower level than the aforesaid shoe, the latter shoe being electrically connected to said electrically operated means and closing the circuit to said electrically operated means through the vehicle and running rail.
8. In an automatic train stop, the combination with the train line pipe of the arresting mechanism on a vehicle, of a pivotal shoe movably supported on the train and projecting therefrom, a rotary valve connected with said train line pipe and operatively connected to said pivotal shoe and operating on the tilting of said shoe to actuate said arresting mechanism, an obstructing member having two distinct levels, said levels being connected by inclined surfaces, the lower level being arranged below and clear of said shoe when in its lowermost position and the inclined faces being adapted to contact with said shoe and tilt it on its pivot, an electrically operated means for raising said pivotal shoe supported on the vehicle and adapted to contact with the lower level of said obstructing member and electrically connected to said electrically operating

means for raising the aforesaid shoe, a battery located in the road bed having one of its terminals electrically connected to said obstructing member and the other terminal connected to the running rail, an electric switch interposed between said battery and one of its terminals, and means for closing said switch.

Copies of this patent may be obtained for five cents each, by addressing the "Commissioner of Patents, Washington, D. C."

Signed at the city of Toronto, county of York, Province of Ontario, in the Dominion of Canada, this 29th day of April 1909.

JAMES HARRY KEIGHLY McCOLLUM.
